UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK, A CORPORATION OF NEW YORK.

INTERLOCKING SYSTEM.

1,399,259.

Specification of Letters Patent.

Patented Dec. 6, 1921.

Application filed January 21, 1920. Serial No. 352,944.

To all whom it may concern:

Be it known that I, WINTHROP K. HOWE, a citizen of the United States, and a resident of the city of Rochester, in the county of Monroe and State of New York, have invented a new and useful Improvement in Interlocking Systems, of which the following is a specification.

This invention relates to interlocking systems for railroads, and more particularly to the construction and operation of the detector locking devices which are usually provided in such systems for preventing the throwing of switches under trains.

In order to prevent a switch being thrown by power under a train or directly in front of it, arrangements may be made to interrupt the control or operating circuits for the switch machine operating said switch, if and while the usual detector track circuit associated therewith is occupied by a train, some suitable arrangement being also provided so as to prevent the switch being left in mid-stroke or unlocked in case the train should enter the detector track circuit while the switch machine is operating. With such an arrangement, the contacts for interrupting the operating circuits have to carry the comparatively large current employed for operating the switch machine, so that I preferably use an auxiliary relay with contacts specially constructed for this purpose, rather than control the operating circuit directly by the contacts of the track relay, said auxiliary relay being controlled by the track relay. The present invention relates more particularly to the manner of control of this auxiliary relay, with the view of operating it by current derived from the main battery at the tower, rather than by a local source of current at the switch which may not be available and which may have to be installed solely for this purpose.

One object of this invention is to provide a simple and efficient means for operating a relay at the switch, subject to the control of the track relay of the detector track circuit, by current from the main source at the tower, and without requiring additional wires running from the tower to the switch machine.

Other objects and features of the invention will be pointed out hereinafter as the description progresses.

In describing the specific embodiments of my invention in detail, reference will be made to the accompanying drawing, in which like reference characters refer to corresponding parts in the several views and in which—

Figure 1 illustrates in a simplified and diagrammatic manner the parts and circuits of a well known type of all-electric interlocking system, with my invention applied thereto, and

Fig. 2 shows a modified construction. 65

For the purposes of explaining the functions and operation of my invention I have shown it applied to a well known system of all-electric interlocking, such as disclosed, for example, in my prior Patent No. 1,288,595, dated December 24, 1918. The construction of the switch machine, and the manner in which it is operated and controlled by a lever at a tower, together with the various circuit controllers and circuits, are explained in my prior patent; and it is deemed sufficient for the purpose of explaining my present invention to refer only briefly to the construction and operation of this type of interlocking system. It should be understood that this particular type of interlocking system is merely illustrative of the utility and nature of my invention, and that the invention may be applied to other types of interlocking systems by making appropriate changes in mechanical details. 85

Referring to the drawings, a stretch of track T, with a switch A, is shown conventionally. The track rails are divided by insulating joints and bonded in the usual way to provide a detector track circuit, comprising a track battery 4 and a track relay 5 having a contact finger or armature 6. The operating parts of the switch machine have not been shown, but the circuit controller 90 for governing the operating and indication circuits, and the operating motor M have been illustrated diagrammatically in the same way as in my prior patent and are designated as a whole SM. This circuit controller includes a contact block 7, which is moved mechanically from its existing extreme position to a middle or intermediate position during the unlocking movement of the switch machine, and is held in this intermediate position until the switch machine has completed its cycle of operation and is again fully locked, whereupon said contact

block is automatically shifted to its opposite extreme position, in the manner fully explained in my prior patent. In connection with my present invention, this contact block 7 is provided with an additional contact piece 8, which is arranged to bridge or electrically connect two contact fingers 9 when said block is in its intermediate position, that is, while the switch machine is operating.

Referring to Fig. 1, the auxiliary relay X for controlling the supply of power to the switch machine is provided with two windings 10 and 11. The winding 10 is designed to close a contact finger or armature 12; and the winding 11 to hold it closed. The winding 10 is preferably made of comparatively high resistance, and the winding 11 of a few turns of large size wire so as to be of low resistance. The contact finger 12 and its co-operating contact are constructed in a manner well known in the art so as to be able to carry without injury the comparatively large operating current of the switch machine. The relay X is also provided with copper tubes or similar means for making it slow releasing, for the purpose hereinafter explained.

In order to enable the maintainer to readily cut off power from the switch machine when he desires to crank it by hand, I provide a cutout plunger 13, guided and supported in a suitable part of the main frame of the switch machine which I have indicated conventionally and designated 14. This cutout plunger 13 is formed with a suitable knob for facilitating its manual movement, and is provided with a key-like projection 15 fitting in a corresponding slot or key-way in its supporting member 14, so that when said plunger is pulled out and partly turned it will be held out. This plunger 13 carries an insulated contact disk 16 arranged to electrically connect contact springs 17 suitably supported on an insulated panel (not shown). A compression spring 18 tends to return said cutout plunger 13 to the normal position shown.

The parts of the interlocking system at the tower (inclosed in a dotted rectangle) comprise the usual lever L, connected to a rod 19 which operates contact blocks, as 20, to bridge pairs of contact springs, as 21. The indication latch for the lever L is designated 22, the indication magnet I, the safety magnet S, the polarized relay PR, the indication selector IS, and the main battery B, these parts being of well known construction and those commonly employed in the dynamic indication type of electric interlocking system illustrated. The various wires and electrical connections will not be described in detail, since the circuits more directly involved in the operation of my invention will be explained hereinafter.

Operation: Referring to Fig. 1, the parts are shown in the normal position. When it is desired to reverse the switch A, the lever is pulled out (to the left as shown) to its reverse indication position, thereby applying energy to the reverse control wire R and energizing the high resistance winding 10 of the auxiliary relay X, providing the detector track circuit is unoccupied, this circuit being traced as follows: commencing at 75 the battery B, wire 23, safety magnet S, wires 24 and 25, magnet 26 of indication selector IS, wire 27, contacts 21 and block 20, wire 28, reverse control wire R, contact springs 30 and contact piece 31, through 80 armature of motor M, contact springs 32 and contact piece 33, wire 34, through field of motor M, wires 35 and 36, winding 10, wire 37, contact finger 6 of the track relay 5, wire 38, contact springs 17 and contact disk 16, 85 common wire C and wire 39 through contacts of polarized relay PR and wire 40 back to the battery B.

Winding 10 being energized, armature 12 is picked up, so that current may flow from the reverse operating wire R through the contacts of pole changer and armature and field of the motor M, along the same path above traced, then along wire 41, low resistance winding 11, wire 42, armature 12, wires 43 and 44, contact springs 17 and contact disk 16 to the common wire C and thence back to the battery B. The winding 11, being of low resistance, does not interfere with the regular operation and indication of 100 the switch machine. When the switch machine completes its operation, the pole changer contact pieces 31 and 33 are shifted and current is cut off from the windings 10 and 11 of the relay X, but the relay being 105 constructed so as to be slow releasing, the armature 12 is held closed long enough to permit the indication current, generated dynamically by the motor M in the usual way, to build up.

If a train should be present upon the detector track circuit when the lever L is operated, the winding 10 of relay X will not be energized, since its energizing circuit above traced will be interrupted at the contact finger 6 of the track relay 5. Consequently, armature 12 is not picked up and the current supplied to the motor M of the switch machine is so small on account of the high resistance of the winding 10 that the switch 120 machine does not operate. Thus, with a train on the detector track circuit, power cannot be applied to the switch machine.

If a train should enter the detector track circuit just after the lever L is moved and while the switch machine is operating, the operating current flowing through the low resistance winding 11 keeps the armature 12 raised and power applied, so that the switch machine may complete its movement. This 130

is preferable to leaving the switch in mid-stroke or unlocked.

If a train should enter the detector track circuit while the switch machine is operating, and if the operator at the tower for some reason should put his lever in the middle position, both the windings 10 and 11 would be deenergized, the winding 10 because its circuit is broken at the contact finger 6, and the winding 11 because the operating current is now cut off from the switch machine. In this instance, the operator would lose his control over the switch machine; and to obviate this objection, the contacts 8-9 are provided, so that while the switch machine is unlocked, a shunt comprising wires 43, 45, contacts 8-9, and wire 46, is established for the armature 12. In order for the operator to lose control of the switch machine in the manner just described, several things must happen just at the right time, and this being a very unlikely contingency, the contacts 8-9 may be omitted if desired, without detracting from the safety 25 of the system.

When it is desired to crank the switch machine over by hand for the purpose of inspection or repair, or because the machine is out of order, the maintainer pulls out the cutout plunger 13 which breaks the main common C at the contact disk 16 so that current cannot be applied to the machine. This is necessary for the protection of the maintainer, since he might be injured by 35 the automatic reversing action characteristic of this type of machine if he should crank the machine fully over with power on. The cut out plunger 13, being positively held in its operated position, cannot be jarred back 40 by a passing train and throw the switch under this train, as sometimes happens with the present practice of lifting the brushes of the motor, since the brushes are sometimes not properly secured.

If the switch machine is cranked over and locked up by hand while a train is present on the detector track circuit, power cannot be applied to the switch machine and cause it to throw the switch points back again, even 50 though the plunger 13 is restored to normal, for the reason that the main common C for the switch machine will be broken at the contacts of the relay X. In this way, when the switch machine is cranked fully over 55 to one position or the other for the purpose of permitting a train to pass, the position of the switch will not be changed by power while a train is passing over it, even though its position is out of correspondence with the 60 lever. This arrangement affords extra safeguards for the hand operation of switches and the flagging of trains over them.

In the modification shown in Fig. 2, the auxiliary relay X¹ is provided with two op-

ositely wound coils or windings 50 and 51, 65 of the same number of turns, thereby constituting in effect a differential relay. These windings are connected in series across the normal and reverse control wires N and R, with high resistances 52 in series therewith. 70 The common terminals of the windings 50 and 51 are connected by a wire 53, armature 6 of the track relay 5, wires 54 and 55, contacts 16-17 to the main common C. Contacts 8 and 9 are provided the same as in 75 Fig. 1, but for a different purpose.

Assuming the switch machine and lever to be normal as shown, the normal control wire N is connected to the battery B at the tower, and current flows from this energized 80 normal control relay N through resistance 52, winding 50, wire 53, armature 6, wires 54, 55, contacts 16-17, and main common C back to the battery B. The other winding 51, however, has practically no current flow- 85 ing in it, since it is shunted or short-circuited by a low resistance path comprising wire 53, armature 6, wires 54 and 55, contacts 16-17, common C, polarized relay PR, indication magnet I, contacts of indication 90 selector IS, lever contacts, and reverse control wire R. Thus, while the armature 6 of the track relay is up, the relay X¹ is unbalanced and its armature 12 attracted. With armature 12 up, operating current may 95 pass through the pole-changer contacts, as 31-33, in the usual way, through motor M, wires 56 and 57, armature 12, wires 58 and 55, and contacts 16-17 to common C.

When a train comes on the detector track 100 circuit, armature 6 of the track relay 5 drops, and the same current then flows through both windings 50 and 51 of the relay X¹; and since these windings are wound equal and opposite, the armature 12 drops, 105 thereby cutting off the supply of current to the switch machine in the same way as previously explained.

If a train should enter the detector track 110 circuit while the switch machine is operating, the armature 12 drops, but the operating current may still flow through the shunt path around said armature and its contact, said shunt path comprising wires 57 and 59, contacts 8-9, and wire 60. The switch machine, therefore, can complete its operation 115 and will not be left in mid-stroke or unlocked. The operation of the cutout plunger 13 and the other parts of the system are the same in this modification as previously 120 explained.

It will be noted that the auxiliary relay X¹ in the modification of Fig. 2 is normally energized, as distinctive from the arrangement in Fig. 1, in which the relay X is 125 normally deenergized. The modification of Fig. 2, therefore, has one disadvantage in that it is normally consuming current. In

- this connection it should be understood that the windings 50 and 51 are made of high resistance, and with external resistances 52 in series therewith, so as to limit the current flow and also prevent interference with the proper operation of the system. For example, I find it preferable to make the resistances of the windings 50 and 51 so as to give with the external resistances 52, a 10 total resistance between the control wires of some 8000 ohms, 4000 on each side.

My invention provides a simple and efficient way of operating an auxiliary relay from the main battery at the tower, subject 15 to the control of the track relay, without running extra wires. The control of this auxiliary relay is such that current cannot be supplied to the switch machine when the detector track circuit is occupied, while the 20 switch machine is always allowed to complete its movement, especially if it should happen to be operating when a train enters the detector track circuit.

Obviously, various illustrations, modifications and adaptations may be made with respect to the particular parts and circuits which I have selected to illustrate the nature of my invention, without changing its functions or operation. For instance, by making 25 the obvious appropriate changes in mechanical details, my improved detector locking means may be applied to other types of interlocking systems, which are either operated or controlled by alternating current or 30 direct current. I desire to have it understood, therefore, that the arrangements and constructions of parts and circuits which I have shown and described are merely illustrative and do not exhaust the various embodiments and forms which my invention 35 may take in practice.

What I claim as new and desire to secure by Letters Patent of the United States, is:

1. In a power operated interlocking system including a central source of energy, a switch machine, a detector track circuit, and means at the switch machine controlled by said track circuit and energized from said central source for preventing application 45 of power to said switch machine while the detector track circuit is occupied, said means when initially energized being maintained energized independently of the track circuit control so long as the switch machine is 50 operating.

2. In a power operated interlocking system including a central source of energy, a switch machine, means including control wires between said source and the switch 55 machine for governing the operation of said machine, a detector track circuit, and means at the switch machine controlled by said track circuit and energized from said central source over said control wires for cut-

ting off the supply of power to said switch machine while the detector track circuit is occupied, said means being ineffective while the switch machine is operating.

3. In a power operated interlocking system for railroads including a central source 70 of energy, a power operated switch machine, a track circuit adjacent to the switch machine, control circuits between the central source and the switch machine for governing the application of power thereto, electrically operable circuit controlling means adapted when deenergized to prevent application of power to the switch machine, said means permitting the switch machine to complete an operation once started prior to 80 the occupancy of the track circuit, an initial energizing circuit for said means having its continuity governed by the track circuit and supplied with current only when current flows in said control circuits. 85

4. In an all-electric interlocking system including a main source of energy at the tower, a switch machine, control circuits for said machine including a common return connection, manually operable means for breaking said common return connection, a detector track circuit, and automatic means controlled by said track circuit for also controlling the continuity of said common return connection. 95

5. In an all-electric interlocking system including a switch machine and an operating circuit therefor, a detector track circuit, and normally inactive means controlled by said track circuit and adapted to be governed from a distant point for making and breaking said operating circuit, said means being energized by the flow of operating current to the switch machine. 100

6. In a power operated interlocking system, a switch machine, a slow releasing electromagnetic device governing the supply of power to said switch machine, a detector track circuit, a circuit controlled by said track circuit for energizing said device, and means for maintaining it energized while said switch machine is operating. 105

7. In an all-electric interlocking system, a switch machine, a circuit for supplying operating current to said machine, a biased 115 normally open circuit controller in said circuit, a detector track circuit, and means controlled by said track circuit for closing said circuit controller and for holding it closed while said switch machine is operating. 120

8. A power interlocking system comprising a switch operating mechanism, a source of current and control means at a distant point for governing the operation of said mechanism, a track circuit, means at the 125. switch controlled by said track circuit and normally acting to prevent application of power to said mechanism, and means re-

- sponsive to the flow of current from said source, for rendering said means ineffective provided the track circuit is not occupied.
9. A power interlocking system comprising a switch operating mechanism, a track circuit, means controlled by said track circuit and normally acting to prevent the application of power to said mechanism while at rest, said means when rendered ineffective 5 acting to continue the supply of power to the mechanism and permit it to complete a cycle of operation once started, a source of current and control means governing the operation of said mechanism from a distant 10 point and also acting to render the first mentioned means ineffective when the track circuit is not occupied.
10. In a railway traffic controlling system, a track including a track circuit, a switch, an electrically controlled mechanism 15 for said switch having an operating circuit, a device located at the switch and having two windings each included in the operating circuit of said mechanism, said device being controlled by said track circuit for preventing 20 the operation of said mechanism when said track is occupied, and for maintaining the circuit of said mechanism throughout its 25 operation.
11. In a railway traffic controlling system, in combination, a track including a track circuit, a switch, an electrically controlled mechanism for operating said switch, a circuit controlling said mechanism, a normally deenergized relay having an operating coil controlled by said track circuit and a holding coil connected in series with the 30 circuit controlling said mechanism, and means operated by said relay for governing the continuity of said circuit.
12. In a railway traffic controlling system, in combination, a track including a track circuit, a switch, an electrically controlled mechanism for operating said switch, a circuit controlling said mechanism, a lever 35 controlling said circuit, a relay having an operating coil controlled by said track circuit and responsive to the flow of current in said circuit and a holding coil connected in series with the circuit controlling said mechanism, and means operated by said relay for governing the continuity of said circuit.
13. In a railway traffic controlling system, a track including a track circuit, a switch, an electrically controlled mechanism for operating said switch, a normally deenergized relay having an operating coil controlled by said track circuit and a holding coil included in the circuit of said mechanism, said relay when energized closing 40 said mechanism circuit, and means for supplying current to said operating coil.
14. In a system for controlling railway switches, a switch operating mechanism, a 45 circuit for governing said mechanism, a track circuit, a relay controlling the application of power to said mechanism, said relay being initially energized by current in said circuit dependent upon the track circuit being unoccupied and also being maintained energized after initially energized until said mechanism has completed a cycle of operation once started.
15. In a system for operating railway switches, a switch operating mechanism having an operating circuit, a track circuit, and a normally deenergized relay at the switch adapted when initially energized to maintain 50 said operating circuit closed while the mechanism is operating, said relay being initially energized by current in the operating circuit provided the track circuit is not then occupied.
16. In a system for operating railway switches, switch operating mechanism having an operating circuit, a track circuit, an electro-magnetic device controlling the application of power to said mechanism, a pick-up circuit for said device energized by 55 current in the operating circuit provided the track circuit is not occupied, and a holding circuit for said device, dependent upon the initial energization thereof, and maintained energized while the mechanism is operating.
17. In a railway traffic controlling system, an electrically operable switch machine, a source of current and control means for governing the switch machine from a distant point, a track circuit, a relay adapted when 60 deenergized to prevent application of current to the switch machine, means controlled by said track circuit and acting when current is supplied to the switch to cause energization of said relay, and means for preventing deenergization of said relay while the switch machine is operating.
18. In a power operated interlocking system, a switch operating mechanism, an electro-magnetic device located at said mechanism for preventing operation thereof, a track circuit, a source of current and control means for governing the operation of said mechanism from a distant point and for also determining the initial energization 65 of said device dependent upon the condition of said track circuit, and means for maintaining said device energized while the switch machine is operating.
19. A power interlocking system comprising a switch operating mechanism, a track circuit, a normally deenergized slow releasing relay adapted to prevent application of power to said mechanism, an energizing circuit for the relay controlled by said track 70 circuit, and a source of current and control means at a distant point for causing energization of the relay when the track circuit is not occupied.
20. A power interlocking system comprising 75

ing a switch operating mechanism, a circuit for governing said mechanism, a track circuit having a track relay, and electrically operable means located at the switch operating

5 mechanism and having an operating winding included in the governing circuit for said mechanism in series with a front contact of the track relay, said means acting when deenergized to prevent operation 10 of the mechanism while the track circuit is occupied.

21. A power interlocking system comprising a switch operating mechanism, a track circuit, an electrically operable device located at said mechanism for preventing operation thereof when the track circuit is occupied, said device after initial energization thereof being ineffective while the mechanism is operating, and means for governing 15 the initial energization of said device from a distant point subject to the control of the track circuit.

22. A power interlocking system comprising an electrically operable switch operating 25 mechanism, a normally deenergized electromagnetic device at said mechanism for preventing application of current thereto, a track circuit, and a source of current and control means at a distant point for supplying current for the operation of said mechanism from said distant point, such supply of current acting to energize said device provided the track circuit is not occupied and thereby permit application of 30 power to the switch operating mechanism.

23. A power interlocking system comprising a switch operating mechanism, a normally deenergized electrically operable means at said mechanism adapted to prevent 40 application of power thereto, a track circuit controlling said means, and manually controlled means for supplying current to said electrically operable means from a distant point subject to the control of said track circuit.

24. A power interlocking system comprising an electrically controlled switch machine, control means for said machine, a track circuit, and electrically operable means located 50 at the switch machine and jointly governed by said track circuit and said control means for preventing application of power to the machine while the track circuit is occupied, and means for independently maintaining 55 the supply of power to the switch machine while it is operating.

25. A power interlocking system comprising an electrically controlled switch operating mechanism, a circuit for governing 60 said mechanism, a track circuit, and an electrically operable device at said mechanism initially controlled jointly by the track circuit and the flow of current in said governing circuit for preventing application of 65 power to said mechanism while the track

circuit is occupied, said device after its initial control permitting the mechanism to complete a cycle of operation started prior to the entrance of a train into the track circuit.

26. A power interlocking system comprising 70 a switch operating mechanism, a normally deenergized electro-magnetic device at said mechanism normally preventing the application of power to the mechanism, a track circuit, and means operable at a distant point for causing energization of said device when the track circuit is not occupied, said device when once energized being automatically maintained energized while the switch mechanism is operated.

27. A power interlocking system comprising 75 a switch operating mechanism, a track circuit, means controlled by said track circuit and normally acting to prevent operation of said mechanism, and means governed 80 from a distant point for rendering said means ineffective when said track circuit is not occupied, said first mentioned means when once rendered ineffective being maintained in that condition so long as operating 85 current is supplied to said mechanism.

28. A power interlocking system comprising 90 an electrically controlled switch machine, a track circuit, means normally acting to prevent operation of the switch machine, 95 a source of current and control means at a distant point for governing said switch machine, and means whereby said normally acting means is automatically made ineffective at times by current from said source 100 under the control of said control means, and subject to the control of said track circuit.

29. A power interlocking system comprising 105 an electrically controlled switch operating mechanism, control means for governing said mechanism from a distant point, a track circuit, and means normally acting to prevent operation of said mechanism and automatically rendered inactive under the control of said control means when the track 110 circuit is not occupied, said means permitting the mechanism to complete a cycle of operation started prior to the entrance of a train into said track circuit.

30. A power interlocking system comprising 115 a switch operating mechanism, a track circuit, means controlled by said track circuit and normally acting to prevent application of power to said mechanism, means for rendering said means ineffective and thereby permit operation of the mechanism when the track circuit is not occupied, and means for maintaining the supply of power to the mechanism so long as it is operating regardless of the condition of said track circuit.

31. A power interlocking system comprising 125 an electrically controlled switch machine, a track circuit, a normally open circuit controller acting to cut off the supply of power to said machine, means controlled 130

- from a distant point for closing said circuit controller to permit operation of said machine when the track circuit is not occupied, and a shunt for said circuit controller closed except when the switch machine is in one or the other of its extreme operated positions. 5
32. A power interlocking system comprising an electrically operable switch machine, a control lever, two control wires and a common return connection between the lever and the switch machine, a detector track circuit, and means at the switch machine energized by current over said wires supplied by the operation of said lever for preventing application of power to the switch machine while said track circuit is occupied. 10
33. A power interlocking system comprising a switch operating mechanism, a lever and control wires for governing the operation of said mechanism from a distant point, a track circuit, and means normally acting to prevent application of power to said mechanism, said means being automatically rendered ineffective by current supplied over said control wires whenever the track circuit is not occupied. 15
34. A power interlocking system comprising a switch operating mechanism, a power supply therefor, a lever and control wires for governing the operation of said mechanism from a distant point, and means normally acting to interrupt the supply of power to said mechanism while it is at rest, said means being automatically rendered inactive by current supplied over the control wires, and being automatically maintained inactive while said mechanism is operating. 20
35. A power interlocking system comprising a switch operating mechanism, a power supply therefor, a lever and control wires for governing the operation of said mechanism from a distant point, a track circuit, and means normally acting to prevent application of power to said mechanism while it is at rest, said means being rendered ineffective when current is supplied over the control wires and the track circuit is not occupied, said means permitting the mechanism to complete an operation once started regardless of the entrance of a train into the track circuit in the meantime. 25
36. A power interlocking system comprising a switch operating mechanism, a lever and control wires for governing the operation of said mechanism from a distant point, a normally deenergized relay controlling the supply of power to said mechanism, a track circuit, and means for causing said relay to be energized by current supplied over the control wires upon operation of the lever provided said track circuit is not then occupied. 30
37. A power interlocking system comprising a switch operating mechanism, a lever and control wires for governing the operation of said mechanism from a distant point, and a device normally acting to prevent operation of the mechanism, said device being automatically rendered inactive when current is supplied over the control wires and the track circuit is not then occupied, said device also permitting the mechanism to complete an operation once started regardless of the entrance of a train into the track circuit in the meantime. 35
38. A power interlocking system comprising a switch machine, a lever and control wires for governing said switch machine from a distant point, a normally deenergized electromagnetic device controlling the supply of power to said machine, a track circuit, means for causing energization of said device by current flowing in said control wires when the track circuit is not occupied, and means for maintaining a supply of power to the machine throughout an operation started, prior to the entrance of a train into the track circuit. 40
39. A power interlocking system comprising a switch operating mechanism, a source of current and control means for governing the operation of said mechanism from a distant point, track circuit controlled means operated by current from said source for preventing application of power to the mechanism, and means actuated in accordance with the movement of the mechanism and effective after the mechanism has started a cycle of operation for independently maintaining the supply of power to the mechanism. 45
40. A power interlocking system comprising a switch operating mechanism, a source of current and control means for governing the operation of said mechanism, a relay having two windings and acting to control the supply of power to said mechanism, a track circuit, and a circuit controller closed when either winding of the relay is energized, one of said windings being energized from said source when the control means is actuated provided the track circuit is not occupied, the other winding being automatically maintained energized after closure of said circuit controller regardless of the condition of the track circuit so long as said mechanism is operating. 50
41. A power interlocking system comprising a switch operating mechanism, a distant source of current, a common return connection between said mechanism and said source in which current flows so long as the mechanism is operating, a track circuit having a track relay, and a relay having two windings and contacts closed when either winding is energized, one of said windings being included in the common return connection in series with a front contact of the track relay, the other winding being included in said common return connection in 55

series with the contacts of the relay itself and being thereby maintained energized after closure of the relay contacts so long as the mechanism is operating regardless of 5 the condition of the track circuit.

42. A power interlocking system comprising a switch operating mechanism, a source of current and control circuits governing the operation of said mechanism, a double wound 10 relay for opening and closing said control circuits and having contacts closed when either of its windings is energized, and a track circuit, one winding of the relay being energized when current flows in said control 15 circuits and the track circuit is not occupied, the other winding being energized while current flows in said control circuits provided the contacts of the relay are closed.

43. A power interlocking system comprising 20 an electrically operable switch machine, a power circuit for said machine, a track circuit, and a relay for governing said power circuit having high and low resistance windings and contacts closed when either winding 25 is energized, the high resistance winding being included in said power circuit when the track circuit is not occupied, the other winding being included in the power circuit when the contacts of the relay are 30 closed and being thereby maintained energized independent of the condition of the track circuit.

44. A power interlocking system comprising 35 a switch operating mechanism, a track circuit, and electro-magnetic means having two windings of high and low resistance respectively, said means being governed by said track circuit and acting to prevent operation of the mechanism while said track 40 circuit is occupied but permitting the mechanism to complete an operation started prior to the occupancy of the track circuit.

45. A power interlocking system comprising 45 an electrically operable switch machine, an operating circuit in which current flows while the switch machine is operating, a normally open circuit controller in said circuit, a relay having a high resistance winding and a low resistance winding each adapted 50 when energized to close the circuit controller, the low resistance winding being included in the operating circuit in series with said circuit controller, and a track circuit for governing the high resistance winding.

46. A power interlocking system comprising 55 an electrically operable switch machine, a track circuit, and a relay having a pick-up winding and holding winding and acting when deenergized to cut off the supply of 60 current to the switch machine, the pick-up winding being energized when current is supplied to the switch machine provided the track circuit is not occupied, the holding winding including contacts of the relay itself and being maintained energized so long 65

as current is supplied to the switch machine irrespective of the condition of the track circuit.

47. A power interlocking system comprising 70 a switch operating mechanism, a control circuit for governing said mechanism from a distant point, a track circuit, and a device responsive to the flow of current in said control circuit and initially dependent upon the condition of said track circuit, said device preventing application of power to said mechanism while the track circuit is occupied and acting to maintain the supply of power throughout a cycle of operation started prior to the entrance of a train into the 75 track circuit.

48. A power interlocking system comprising 80 an electrically operable switch machine adapted to give a dynamic indication, and track circuit controlled means responsive to 85 the flow of operating current to the switch machine for governing the operating circuits thereof, said means being slow releasing to permit transmission of the indication impulse. 90

49. A power interlocking system comprising 95 a switch operating mechanism, operating and indication circuit for said mechanism including a common wire, a slow releasing relay for governing the continuity of the common wire, and track circuit controlled means for governing said relay. 100

50. A power interlocking system comprising 105 a switch operating mechanism, a slow releasing double wound relay controlling the application of power to said mechanism, and a track circuit, one winding of the relay being controlled by the track circuit, and the other winding in accordance with the operation of the mechanism. 110

51. A power interlocking system comprising 115 a switch operating mechanism, a circuit controller actuated in accordance with the movements of said mechanism and closing except when the mechanism is in one or the other of its extreme operating positions, a double wound relay and contacts closed when either winding is energized, a track circuit adjacent to the switch operated by said mechanism, an energizing circuit for one 120 winding of the relay controlled by the track circuit, an energizing circuit for the other winding of the relay including the contacts of the relay itself, and a shunt for the contacts of said relay closed when said circuit controller is closed.

52. A power interlocking system comprising 125 a switch operating mechanism, a manually operable device adapted to be actuated and cut off the supply of power to said mechanism to permit operation thereof by hand, track circuit controlled means for independently governing the supply of power to the mechanism, and means acting to apply power to the mechanism when the manually oper- 130

able device is restored to normal regardless of the condition of the track circuit provided the mechanism is only partly operated.

53. A power interlocking system comprising an electrically controlled switch machine, a source of current and a lever at a distant point for governing the operation of said machine, a track circuit, and means jointly controlled by the track circuit and by the 10 lever for preventing an operation of the machine from rest while the track circuit is occupied, but permitting the machine to complete a cycle of operation started prior to the entrance of a train into the track circuit, 15 said means being adapted to permit the machine to be operated to either position in correspondence with the lever while the track circuit is occupied if the machine is operat-

ing at the time the track circuit becomes occupied.

54. An interlocking system comprising a switch operating mechanism, a track circuit, said mechanism having its operation from rest dependent upon the condition of the track circuit, normal and reverse control 25 circuits of said mechanism, and means effective upon energization of either control circuit to permit operation of the mechanism if it is operating at the time the track circuit becomes occupied, whereby control of the 30 mechanism is not lost upon the entrance of a train into the track circuit while the mechanism is operating although the operator may shift his lever.
